United States Patent Office

Des. 179,896
Patented Mar. 19, 1957

179,896

MINIATURE CAR

Hubert H. Hackney, Guilford College, N. C., assignor to
Gordon W. Morton Company, Guilford, N. C., a cor-
poration of North Carolina

Application August 19, 1955, Serial No. 37,588

Term of patent 14 years

(Cl. D34—15)

FIG. 1

FIG. 2

FIG. 3

FIG. 4

Fig. 1 is a side perspective view of a miniature car, showing my new design;

Fig. 2 is a front perspective view thereof;

Fig. 3 is a top plan view thereof; and

Fig. 4 is a rear elevational view thereof.

The dominant features of my new design are shown in solid lines in the drawing.

What is claimed is:

The ornamental design for a miniature car, substantially as shown and described.
